Primary Examiner — Angela J Lee(74) *Attorney, Agent, or Firm* — Christensen O'Connor Johnson Kindness PLLC(57) **CLAIM**

The ornamental design for a light, as shown and described.

DESCRIPTION

FIG. 1 is a bottom isometric view of a light according to the first embodiment of my new design;

FIG. 2 is a bottom plan view thereof;

FIG. 3 is a top plan view thereof;

FIG. 4 is a side elevation view thereof;

FIG. 5 is another side elevation view thereof;

FIG. 6 is another side elevation view thereof; and

FIG. 7 is another side elevation view thereof.

FIG. 8 is a bottom isometric view of a light according to the second embodiment of my new design;

FIG. 9 is a bottom view thereof;

FIG. 10 is a top plan view thereof;

FIG. 11 is a side elevation view thereof;

FIG. 12 is another side elevation view thereof;

FIG. 13 is another side elevation view thereof; and,

FIG. 14 is another side elevation view thereof.
